(57) CLAIM

The ornamental design for a scarf organizer, as shown and described.

DESCRIPTION

FIG. 1 is a front perspective view of the scarf organizer; FIG. 2 is a top plan view of the scarf organizer of FIG. 1; FIG. 3 is a bottom plan view of the scarf organizer of FIG. 1; FIG. 4 is a left elevational view of the scarf organizer of FIG. 1; FIG. 5 is a right elevational view of the scarf organizer of FIG. 1; FIG. 6 is front elevational view of the scarf organizer of FIG. 1; and, FIG. 7 is a back elevational view of the scarf organizer of FIG. 1. The scarf organizer is shown broken to represent indeterminate length. The indeterminate portion of the article forms no part of the claim design. Patentability is based only on those portions of the scarf organizer that are shown in solid lines.

1 Claim, 3 Drawing Sheets
